SURFACE CONDENSER

Wesley M. Nagle, Cambridge, Mass.

Application December 11, 1933, Serial No. 701,780

18 Claims. (Cl. 257—24)

This invention relates to heat interchange apparatus, such as surface condensers, in which vapor is condensed by the transfer of heat to a cooling fluid through a wall interposed therebetween. It is the object of the invention to improve the efficiency of such apparatus.

In apparatus of this general character the vapor condenses upon the wall which separates it from the cooling fluid and wets the wall so that a thick layer of condensate always is present upon the condensing surface, that is, the surface of the wall adjacent the vapor. This thick layer of condensate insulates the condensing surface and seriously limits the condensing capacity of the apparatus, namely, limits the amount of vapor that may be condensed per unit time with a unit area of condensing surface and with a given difference in temperature between the vapor and the cooling fluid.

The present invention contemplates a method of treating the condensing surface of apparatus of this general type to modify the condensing surface substantially permanently so that it is not wetted by the condensate and so that the latter is caused to gather together in the form of drops on the condensing surface, leaving a substantial fraction of the condensing surface directly exposed to the vapor and available for effecting heat transfer at a maximum rate. Thus, the condensing surface is treated to leave a thin film of an agent which has the ability to cling tenaciously to the condensing surface and not be washed away by the normal action of the vapor or its condensate and which is non-wettable by the condensate. The treating agent is used in such quantity as to form an extremely thin adsorbed film upon the condensing surface so as not to introduce a substantial additional thermal resistance. The drop-wise condensation effected in accordance with the invention increases several times the individual coefficient of heat transfer from condensing steam to a solid surface expressed as the quantity of heat transfer per unit time per unit surface area per unit difference in temperature between the steam and the condensing surface.

It has been discovered that agents containing compounds having one or more non-polar parts or hydrocarbon radicals attached to an active polar group are capable of promoting lasting drop-wise condensation of steam when the compound is applied on metals of moderate smoothness. The polar group of these compounds probably causes the compound to adsorb on the surface of the metal or form an insoluble com-

pound with the metal while the hydrocarbon group probably serves to render the metal surface non-wettable to water. Entirely non-polar compounds, such as the paraffin hydrocarbons, do not cling tenaciously to the surface of the metal and, consequently, are not suited for promoting drop-wise condensation. The higher fatty acids, such as oleic, stearic and palmitic acids, are well suited for promoting lasting drop-wise condensation of steam on moderately smooth tubes of copper, brass, admiralty metal, Monel metal, nickel and chrome-nickel steels. Fats and waxes which contain the higher fatty acids may also be used. Organic compounds containing bivalent sulphur, such as the xanthates, dithiophosphates and mercaptans, are well suited for promoting drop-wise condensation of steam on copper and copper alloys, such as brass and Monel metal. Particularly good results have been obtained with potassium amyl, xanthates, potassium ethyl xanthates, amyl mercaptans and benzyl mercaptans. In general, those compounds of the classes of organic compounds above mentioned which contain the so-called larger hydrocarbon radicals are more effective in promoting drop-wise condensation than those which contain the smaller hydrocarbon radicals.

The treating agent may be applied by rubbing the condensing surface with a cloth moistened with the agent or with a solution of the agent in a suitable solvent or by introducing the agent or its solution into the steam chamber as a spray or vapor. The agent may be applied by washing the steam chamber with a solution or an emulsion of the treating agent. If the condensing surface is rough it should be made moderately smooth by grinding or buffing. The treating agent may be applied subsequent to the smoothing operation or the two operations may be combined by mixing the treating agent with the abrasive.

The single figure of the accompanying drawing is a detail fragmentary sectional view of one wall of a surface condenser which separates the vapor to be condensed and the cooling fluid. As illustrated, the surface of the wall 10 adjacent the vapor to be condensed is provided with an adsorbed film 11 of any one of the treating agents above mentioned. It will be noted that the film 11 is united to the surface of the wall 10 by a bond, as indicated at 12, which probably is brought about by a union between the treating agent and the metal to form an insoluble compound. The vapor to be condensed condenses upon the surface of the film 11 in the form of drops 13 which roll off without wetting the film 11 and leave

numerous areas 14 directly exposed to the vapor.

The following is illustrative of the advantages of the invention. When condensing saturated steam on a clean nickel tube in a small falling film 5 condenser the over-all coefficient of heat transmission was found to be 456 B. t. u. per square foot, per hour per degree Fahrenheit difference between the temperatures of the steam and the cooling water but when the tube was treated with 10 oleic acid drop-wise condensation resulted and the over-all rate of heat transfer rose to 950. Had the thermal resistance through the tube and on the cooling water side of the tube been less than what was employed, the gain in condensing efficiency would have been even more striking.

Using an apparatus treated in accordance with the invention I have secured drop-wise condensation of steam at thermal current densities many fold that obtained in a typical surface condenser 20 in a power plant. In the above example, the thermal current density was 135,000 British thermal units per hour per square foot of condensing surface.

I claim:

- 25 1. The method of improving the condensing efficiency of heat interchange apparatus in which vapors are condensed by the transfer of heat to a cooling fluid through a wall interposed therebetween which comprises forming upon the surface 30 of said wall with which the vapors contact a film of a material which has the property of tenaciously resisting removal by the normal action of said vapor and its condensate and is non-wettable by said condensate.
- 35 2. The method of improving the condensing efficiency of heat interchange apparatus in which steam is condensed by the transfer of heat to a cooling fluid through a wall interposed therebetween which comprises forming upon the surface 40 of said wall with which the steam contacts a film of an organic compound having a non-polar part attached to a polar part and capable of clinging tenaciously to said surface and which is non-wettable by water.
- 45 3. The method of improving the condensing efficiency of heat interchange apparatus in which steam is condensed by the transfer of heat to a cooling fluid through a wall interposed therebetween which comprises forming upon the surface 50 of said wall with which the steam contacts a film of a compound selected from the group which consists of fatty acids and organic compounds containing bivalent sulphur, said compound containing a non-polar part and a polar part.
- 55 4. The method of improving the condensing efficiency of heat interchange apparatus in which steam is condensed by the transfer of heat to a cooling fluid through a wall interposed therebetween which comprises forming upon the surface 60 of said wall with which the steam contacts a film of a fatty acid.
- 65 5. The method of improving the condensing efficiency of heat interchange apparatus in which steam is condensed by the transfer of heat to a cooling fluid through a wall interposed therebetween which comprises forming upon the surface of said wall with which the steam contacts a film of a dithiophosphate.
- 70 6. The method of improving the condensing efficiency of heat interchange apparatus in which steam is condensed by the transfer of heat to a cooling fluid through a wall interposed therebetween which comprises forming upon the surface 75 of said wall with which the steam contacts a film of a mercaptan.

7. A heat interchange apparatus in which vapor is condensed by the transfer of heat to a cooling fluid through a wall interposed therebetween wherein the surface of said wall upon which said vapor condenses has a thin adsorbed film of a material which clings tenaciously to the wall and resists removal by the normal action of said vapor and its condensate and is non-wettable by said condensate. 5

8. A heat interchange apparatus in which 10 steam is condensed by the transfer of heat to a cooling fluid through a wall interposed therebetween wherein the surface of said wall upon which said steam condenses has a thin adsorbed film of an organic compound having a non-polar part 15 attached to a polar part and capable of clinging tenaciously to said surface and which is non-wettable by water.

9. A heat interchange apparatus in which steam is condensed by the transfer of heat to a 20 cooling fluid through a wall interposed therebetween wherein the surface of said wall upon which said steam condenses has a thin adsorbed film of a compound selected from the group which consists of fatty acids and organic compounds 25 containing bivalent sulphur, said compound containing a non-polar part and a polar part.

10. A heat interchange apparatus in which steam is condensed by the transfer of heat to a cooling fluid through a wall interposed therebetween wherein the surface of said wall upon which said steam condenses has a thin adsorbed film of a fatty acid. 30

11. A heat interchange apparatus in which steam is condensed by the transfer of heat to a 35 cooling fluid through a wall interposed therebetween wherein the surface of said wall upon which said steam condenses has a thin adsorbed film of a dithiophosphate.

12. A heat interchange apparatus in which 40 steam is condensed by the transfer of heat to a cooling fluid through a wall interposed therebetween wherein the surface of said wall upon which said steam condenses has a thin adsorbed film of a mercaptan.

13. The method of improving the condensing efficiency of heat interchange apparatus in which steam is condensed by the transfer of heat to a cooling fluid through a wall interposed therebetween which comprises forming upon the surface 50 of said wall with which the steam contacts a film of a compound selected from the group which consists of the higher fatty acids and organic compounds containing bivalent sulphur, said compound containing a non-polar part and a polar part. 55

14. The method of improving the condensing efficiency of heat interchange apparatus in which steam is condensed by the transfer of heat to a cooling fluid through a wall interposed therebetween which comprises forming upon the surface of said wall with which the steam contacts a film of a higher fatty acid. 60

15. A heat interchange apparatus in which steam is condensed by the transfer of heat to a cooling fluid through a wall interposed therebetween wherein the surface of said wall upon which said steam condenses has a thin adsorbed film of a compound selected from the group which consists of the higher fatty acids and organic compounds containing bivalent sulphur, said compound containing a non-polar part and a polar part. 65

16. A heat interchange apparatus in which steam is condensed by the transfer of heat to a 70 75

cooling fluid through a wall interposed there-between wherein the surface of said wall upon which said steam condenses has a thin adsorbed film of a higher fatty acid.

5 17. The method of improving the condensing efficiency of heat interchange apparatus in which steam is condensed by the transfer of heat to a cooling fluid through a wall interposed there-between which comprises forming upon the surface of said wall with which the steam contacts

10 a film of an organic compound containing bivalent sulphur, said compound containing a non-polar part and a polar part.

18. A heat interchange apparatus in which steam is condensed by the transfer of heat to a cooling fluid through a wall interposed there-between wherein the surface of said wall upon which said steam condenses has a thin adsorbed film of an organic compound containing bivalent sulphur, said compound containing a non-polar part and a polar part.
